OPEN POT OIL BURNER WITH UNBALANCED
AIR SUPPLY

Leon D. Mills, Tacoma, Wash.

Application June 30, 1947, Serial No. 758,075

5 Claims. (Cl. 158—91)

1

The invention relates to open pot oil burners of the general type in which the oil burning pot is enclosed by an air supply jacket which receives air under pressure from a blower, the side wall of the pot being formed with primary and secondary air inlet openings for conducting air from said jacket into the pot to support combustion. The primary air inlet openings are near the bottom of the pot and have the function of supporting sufficient combustion in this region to heat the pot for vaporization of oil and to maintain a pilot or low fire. The secondary air inlet openings are above the primary openings and admit all other air necessary for complete combustion of all oil vapors.

While burners of the type in question are operating at high flame, the flow of oil tends to build up and form a puddle on the pot bottom, and when the air and fuel supply means are adjusted (usually synchronously) for low flame, this pool of oil is left to be burned, but the supply of primary air to this pool is then insufficient to support complete combustion of such a large amount of oil, with the result that the burner smokes and forms soot and carbon. Other burners of this type are also limited as to the maximum amount of oil which can be vaporized and burned cleanly and still maintain a clean low pilot flame.

My invention provides an improved burner which will consume all oil admitted to the pot during high flame operation and which will burn a greater amount of fuel on high flame than conventional burners of the same size while still having the ability to operate on a very low pilot flame and the ability to change from high flame to low flame without the period of improper combustion found in other burners of this type. I attain this result by a novel construction which injects a much greater amount of air through the primary air inlet openings than usual during high flame operation, and shields the pot bottom against the cooling effect of the air being rapidly blown into the air jacket. By so doing, greater combustion occurs in the bottom zone of the pot and its temperature is maintained sufficiently high to rapidly vaporize the oil for thorough burning instead of allowing a pool to accumulate; and with a relatively small burner, I am enabled to produce a greater range of heats than heretofore possible with this type of burner.

Figure 1 of the accompanying drawings is a vertical sectional view on line 1—1 of Fig. 3.

Fig. 2 is an enlarged fragmentary vertical section similar to the lower left portion of Fig. 1.

Fig. 3 is a view partly in top plan and partly in horizontal section, as indicated by line 3—3 of Fig. 1.

Fig. 4 is an enlarged detail section similar to the upper left portion of Fig. 1.

A preferred construction has been illustrated and will be rather specifically described, but it is

2

to be understood that minor variations may be made within the scope of the invention as claimed.

A pot 5 is shown having a centrally depressed bottom 6 and a cylindrical side wall 7, said side wall being provided with an oil inlet 8 near its lower end and having a lateral continuous flange 9 at its upper end. An upper burner ring 10 rests on this flange 9, and a lower burner ring 11 rests on lugs or the like 12 projecting inwardly from the lower portion of the side wall 7. Below the lower ring 11, the side wall 7 is formed with circumferentially spaced primary air inlet openings 13, and above said ring 11, is formed with secondary air inlet perforations 14.

15 An air jacket 15 encloses the pot 5, said jacket comprising a cylindrical side wall 16 spaced outwardly from the pot side wall 7, and a bottom 17 spaced downwardly from the pot bottom 6. Directly above its bottom 17, the jacket 15 is provided with an inlet 18 for air under pressure from a blower. The upper end of the wall 16, in the present disclosure, is provided with an inwardly projecting flange 19 upon which the flange 9 of the pot 5 rests, the two flanges thus closing the upper end of the space between the side walls 7 and 16.

20 A cylindrical shield wall 20 is interposed between the pot side wall 7 and the jacket side wall 16 and terminates below the flanges 9 and 19. 30 This shield wall 20 divides the space between the two side walls 7 and 16, into an up-flow passage 21 and a down-flow passage 22 which communicate with each other at their upper ends. The lower end of the up-flow passage 21 communicates with 35 the lower portion of the air jacket 15, and the lower end of the down-flow passage 22 is closed by the peripheral portion of a bottom plate 23, said bottom plate being joined to the lower edge of the shield wall 20 and being disposed in contact with the lower side of the bottom 6 of the pot 5.

40 I provide communicating means between the up-flow passage 21 and the primary air inlet openings 13, which means segregates these openings 13 from the down-flow passage 22. In the present construction, the means in question consists of substantially conical nipples 24 stamped inwardly from the jacket side wall 16 and abutting the pot side wall 7. Said nipples 24 decline inwardly to direct the primary air downwardly 45 through the openings 13 and toward the bottom of the pot. The inner ends of these nipples directly communicate with the primary air inlet openings 13 and these openings also preferably decline inwardly as shown more particularly in 50 Fig. 2, to direct the primary air downwardly toward the bottom 6 of the pot 5.

55 I also provide air-flow restricting means so associated with the up-flow passage 21 as to slow down the discharge of air from said up-flow passage 21 into the down-flow passage 22, during high-flame operation of the burner, at which

time, the air enters the jacket 15 under considerable pressure and at relatively high velocity, from the inlet 18. Thus, the air pressure in the jacket 15, below the air-flow restricting means, will be greater than that above said means, with the result that the primary air will be forced in abundance through the nipples 21 and openings 13, thus supporting such thorough combustion in the bottom zone of the pot 5, that no pool of oil will accumulate therein. Contributing to this result, is the bottom plate 23 which contacts with the pot bottom 6, for said plate 23 prevents as much chilling of the pot bottom 6, from contact with the ingoing air, as would ordinarily occur, thus aiding in keeping the bottom zone of the pot at such a high temperature as to thoroughly vaporize the oil as fast as it enters.

The air-flow restricting means above discussed, is preferably in the form of a choke ring 25 projecting inwardly from the jacket side wall 16 into close relation with the shield wall 20. In the present disclosure, this choke ring 25 is somewhat below the upper end of the wall 20, but it could be located either higher or lower.

During high-flame operation of the burner, the primary air is forced in abundance through the nipples 24 and primary air inlet openings 13 to support thorough combustion of the fuel entering through the inlet 8, and due to this thorough combustion and the protection of the pot bottom 6 against the cooling effect of the ingoing air, by means of the plate 23, unusually high temperature will exist in the bottom zone of the pot, with the result that the ingoing fuel will be rapidly vaporized instead of accumulating in a pool. During this high-flame burner operation, the air pressure in the down-flow passage 22 will be considerably less than that in the up-flow passage 21, below the choke ring 25, but said pressure will be ample to supply the required auxiliary air to the pot through the openings 14, to support thorough combustion. When the supplies of air and oil are adjusted for low-flame, there is no pool of oil left upon the bottom of the pot which must first be burned out, as is the case with most pot type burners. This action allows a much larger volume of oil to be vaporized in a given size pot than has been possible heretofore and still maintains the same low fire efficiency. In other burners, as soon as adjustment is made for low flame, the air pressure within the jacket 15 is insufficient to supply ample air through the openings 13 to support combustion of a relatively large quantity or pool of oil, with the result that heretofore smoking of the burner has occurred, creating soot and carbon. With the improved construction, while the air pressure below the choke ring 25 (at low flame) is not appreciably higher than that above said choke ring, due to the very low velocity of the ingoing air and its relatively slight pressure, nevertheless sufficient air can enter through the primary openings 13 to support thorough combustion of the mere trickle of oil then entering, and no smoking and carbonizing occurs.

From the foregoing, taken in connection with the accompanying drawings, it will be seen that novel and advantageous provision has been made for carrying out the objects of the invention, and while preferences have been disclosed, attention is again invited to the possibility of making variations within the scope of the invention as claimed.

I claim:

1. An oil burner comprising a pot having an oil

inlet, said pot comprising a bottom and a side wall, said side wall having a series of primary air inlet openings in its lower portion and having secondary air inlet perforations above said primary air inlet openings, an air supply jacket enclosing said pot, said jacket having a side wall surrounding and spaced from said pot side wall and having a bottom spaced downwardly from said pot bottom, said jacket having an inlet in its lower portion for admitting air under pressure and being closed at its upper end, a continuous shield wall in the space between said side walls of said pot and jacket and dividing said space into an up-flow passage adjacent said jacket side wall and a down-flow passage adjacent said pot side wall, the lower end of said up-flow passage being open to receive air from the lower portion of said jacket, the lower end of said shield cooperating with said pot to close the lower end of said down-flow passage, the upper ends of said up-flow and down-flow passages being in communication with each other, primary air conducting means placing said up-flow passage in communication with said primary air inlet openings and segregating these openings from said down-flow passage, and air-flow restricting means above said air-conducting means and so associated with said up-flow passage as to cause lower air pressure in the upper portion of said jacket than in the lower portion thereof when air is supplied to said jacket under relatively high pressure; whereby, while the air and oil supplies remain adjusted for high-flame, sufficient air will be forced through said primary air inlet openings to insure combustion of all oil then entering the pot, thereby preventing a pool of oil from being left in said pot when the supplies of air and oil are reduced for low flame.

2. A structure as specified in claim 1; said primary air-conducting means consisting of nipples projecting inwardly from said shield wall and abutting said pot side wall.

3. A structure as specified in claim 1; said air flow restricting means consisting of a choke ring on said jacket side wall and extending into close relation with said shield wall.

4. A structure as specified in claim 1; together with a bottom plate secured to the lower end of said shield wall and contacting with the lower side of the pot bottom to shield the latter against the cooling effect of the air entering said jacket and to transmit heat radiated from the sides of the pot back to the bottom of the pot thereby increasing pot bottom temperatures and permitting vaporization of a greater amount of fuel.

5. A structure as specified in claim 1; said primary air conducting means consisting of means associated with said primary air inlet openings for directing the primary air downwardly through the same toward the pot bottom.
